UNITED STATES PATENT OFFICE.

ORVILLE M. MORSE, OF JACKSON, MICHIGAN.

FEED-REGULATOR.

No. 895,489.

Specification of Letters Patent. Patented Aug. 11, 1908.

Application filed March 18, 1907. Serial No. 363,025.

To all whom it may concern:

Be it known that I, ORVILLE M. MORSE, a citizen of the United States of America, residing at Jackson, in the county of Jackson 5 and State of Michigan, have invented certain new and useful Improvements in Feed-Regulators, of which the following is a specification, reference being had therein to the accompanying drawings.

10 It is the object of the invention to obtain a feed mechanism for granular or comminuted material, in which the quantity of material fed in a given interval of time may be regulated to a high degree of accuracy.

15 To this end, the invention consists in the construction as hereinafter set forth.

In the drawings, Figure 1 is a perspective view of one form of the apparatus; Fig. 2 is a vertical section in the plane of the adjustable 20 feed spout; Fig. 3 is a section through a modified form of the apparatus; and Figs. 4 and 5, are diagrammatic sectional views, illustrating the principle underlying the construction.

My invention is based on the principle that 25 the angle of the sides of a pile of granular or comminuted material remains practically constant under uniform conditions. Thus, if the granular or comminuted material is fed on a disk, or flat plate of any kind, so as to 30 cover the entire surface, it will rise in a pyramidal form, the angle of the sides being determined by the nature of the material employed. Again, if granular or comminuted material is fed through an aperture 35 upon a horizontal plate arranged beneath the same, it will spread out at the base, but only to a limited extent.

Based upon the principle as above stated, I have devised a construction of feed mechanism in which the granular or comminuted material is fed over the edge of one plate on 40 to a lower plate, being permitted to assume its natural angle, and the pyramidal pile thus formed is then moved laterally to discharge 45 the same, being immediately replaced by a new supply from the upper plate or ledge. This may be accomplished in two ways, illustrated diagrammatically respectively in Figs. 4 and 5. In Fig. 5, the material A' is fed 50 through an aperture B' in a plate C' upon a lower plate D'. In Fig. 4 a plate E', having an aperture F', is provided with a superposed guard plate G' above the aperture. This guard plate is of sufficient size to prevent the 55 spreading of the material when actuated by gravity alone so as to discharge through the

aperture F' therebeneath. If, however, the pile of material resting on the base E' is moved laterally, as by a sweep H', it will be discharged through the aperture F' at a rate 60 determined by the speed of the sweep. In like manner, a lateral movement of the pile of material, as shown in Fig. 5, resting upon the plate D', will permit a further discharge of the material through the aperture B', but 65 as soon as lateral movement ceases, further feeding through the aperture B' is arrested.

With either of the devices described, the rate of discharge of the material is a function of the area of the aperture, the height of the 70 space between the upper and lower plates, and the speed of the lateral movement imparted to the material. If these factors remain constant, the rate of discharge is constant, but a variation in one or more of the 75 factors will produce a corresponding variation in the rate of discharge.

The preferred form of the embodiment of my invention is illustrated in Figs. 1 and 2, and is of the following construction: A is a 80 stationary receptacle, or holder, for the supply of granular or comminuted material. B is the bottom plate of this receptacle, which is provided at one point, preferably near the periphery, with a discharge aperture C. D 85 is a disk, or revoluble plate, beneath the receptacle A, which is mounted upon a shaft E, and is driven at a constant rate of speed by suitable mechanism, such as the worm wheel F and the worm G, the latter being on a 90 shaft H, driven by the pulley I from a suitable source of power.

Depending from the receptacle A, in registration with the aperture C, is a discharge spout J, having its discharge end vertically 95 adjustable in relation to the surface of the disk B, preferably by providing a member K having a threaded engagement with the member J. Thus the granular or comminuted material will be fed from the receptacle 100 A through the spout J onto the disk B, spreading out upon said disk to a determined width dependent upon the height of the discharge end K of the spout above the disk. If the disk is revolved at a constant rate of 105 speed through the mechanism described, the material will be fed thereon at a uniform rate, producing a circular column of uniform width and depth. Before the revolution of the disk is completed, this column of granular or comminuted material is deflected laterally over the edge of the disk by a suitable 110

scraper L, which is shown and is provided with two scraping blades M and N.

As has been stated, the spreading of the granular or comminuted material upon the supporting base will be constant under uniform conditions, but will vary to some extent by variation in pressure. I, therefore, preferably provide a guard plate O, above the discharge aperture C for relieving the material in the spout J from the pressure of the weight of the material in the receptacle A. I have further provided a sweep, formed by the radial arms P, mounted upon the shaft E, which extends into the receptacle A, these arms moving the material laterally to fill the spout J.

This feed mechanism is capable of extreme nicety of adjustment, as the height of the extension member K of the discharge spout may be adjusted by screwing it up or down on the threaded member J.

As a modification, the construction illustrated in Fig. 3 may be employed, in which the rate of feed is determined by the rate of travel of a sweep P' within the receptacle A'. This sweep P' moves the material laterally beneath the guard plate O', which is above the discharge aperture C', permitting the displaced material to fall through said aperture. The rate of feed may be varied by an adjustable plate R, which increases or diminishes the area of the aperture C'. This modification is not as desirable a structure or as accurate in its operation as the one illustrated in Figs. 1 and 2, but, in a broad sense, it embodies the same principle of operation.

What I claim as my invention is:

1. In a feed mechanism for granular or comminuted material, the combination with a holder for the granular or comminuted material, having an apertured bottom, of a plate in said holder directly above said aperture, and a second plate beneath said aperture revolvable about an axis eccentric thereto, and adapted to support the material fed through the aperture and means for deflecting the material over the edge of said revolvable plate.

2. A feed mechanism for granular or comminuted material comprising a holder for the material, having an apertured bottom, a plate arranged parallel to said bottom directly above said aperture, means for moving the material laterally between said plate and apertured bottom of the receptacle, and a traveling plate arranged beneath said aperture for supporting the material fed through said aperture.

3. In a feed mechanism for granular or comminuted material, the combination with a holder for the granular or comminuted material, having an apertured bottom, of a plate in said holder directly above said aperture, a second plate beneath said aperture revolvable about an axis eccentric thereto

adapted to support the material fed through the aperture, and means independent of said plates for adjusting the rate of discharge.

4. In a feed mechanism, the combination with a holder for the granular or comminuted material, of an adjustable discharge spout depending from said holder, a revoluble plate arranged beneath said spout and traveling transversely thereto, said spout being adjacent to the periphery of said revoluble plate whereby in the rotation of said plate a column of granular or comminuted material of uniform width is deposited thereon, and means for deflecting the material over the periphery of said plate before the completion of the revolution thereof.

5. In a feed mechanism, the combination with a holder for the granulated or comminuted material, having an apertured bottom, a plate in said holder directly above the aperture, an adjustable discharge spout depending from said aperture, a traveling plate beneath said discharge spout, and means for deflecting the material over the edge of said traveling plate.

6. In a feed mechanism, the combination with a holder for the granulated or comminuted material having an apertured bottom, a plate directly above the aperture, means for moving the material laterally between said plate and the bottom, a discharge spout depending from said aperture, a traveling plate beneath said discharge spout and a scraper adapted to laterally deflect the material over the edge of said traveling plate.

7. A feed mechanism for granular or comminuted material comprising a holder provided with a discharge aperture in the bottom thereof eccentric to the axis of said holder, a plate arranged parallel to said bottom spaced therefrom and guarding the aperture therein, means for moving the material laterally between said plate and discharge aperture, and means for variably adjusting the distance between said discharge aperture and plate.

8. A feed mechanism for granular or comminuted material comprising a holder for the material provided with an aperture in the bottom of said holder eccentric to the axis of the holder, a discharge spout for said aperture, a plate arranged parallel to said bottom spaced therefrom and guarding the aperture therein, means for moving the material laterally between said plate and discharge spout, and means for variably adjusting the distance between the outer end of said discharge spout and said traveling plate.

9. In a feed mechanism, the combination with a holder for the granular or comminuted material, a discharge spout for said holder, a traveling plate beneath said holder and spaced therefrom having its axis of rotation eccentric to said discharge spout, and means for variably adjusting the distance between said

spout and plate whereby the discharge of said material is regulated.

10. A feed mechanism for granular or comminuted material comprising a holder, a discharge spout for said holder, a plate beneath said holder and spaced therefrom traveling transversely to said spout and adapted to present different portions in registration therewith, means for moving the material

laterally between the discharge spout and plate, and means for variably adjusting the distance between said spout and plate.

In testimony whereof I affix my signature in presence of two witnesses.
